UNITED STATES PATENT OFFICE.

GEORGE H. GILMAN, OF BOSTON, MASSACHUSETTS.

DRILLING MACHINE.

Application filed February 25, 1920. Serial No. 361,170.

My invention relates to drilling machines and particularly, but not exclusively, to those in which the drilling tool is operated linearly and angularly by means of separate motors.

My invention will be best understood from the following description when read in the light of the accompanying drawings of one specific embodiment of my invention submitted for illustrative purposes, while the scope of my invention will be more particularly pointed out in the appended claims.

In the drawings:

Fig. 1 shows a transverse section of the submitted embodiment of my invention;

Figs. 2 and 3 respectively are sections on the lines 2—2 and 3—3 of Fig. 1;

Fig. 4 is a section on the line 4—4 of Fig. 2;

Fig. 5 is a section on the line 5—5 of Fig. 1; and

Fig. 6 is a section on the line 6—6 of Fig. 2.

In the submitted embodiment of my invention I provide a drill steel, which I operate linearly by percussive action imparted by a hammer piston and angularly by imparting thereto rotation by means of a rotary motor.

The piston just referred to I provide with an enlarged head 1 and with oppositely extending stem portions 2 and 3 of reduced diameter. The piston I mount for reciprocation within a cylinder structure having bores which fit the head 1 and the stems 2 and 3, the cylinder and piston thereby providing the expansible chambers 4, 5 and 6 to which motive fluid may be admitted to act on the effective areas of the piston to move it.

For supplying motive fluid I have shown a conduit 7 adapted when the machine is in operation to be permanently connected with the source of motive fluid supply. This conduit herein communicates with an annular groove 8 formed adjacent the front end of the bore receiving the rearwardly extending stem 3 of the piston. The stem 3 in my submitted embodiment is subjected continuously to the pressure of the motive fluid and for causing this I herein connect the rearward end of the bore receiving the stem to the groove 8 by means of conduits 9 formed in the wall of the cylinder.

The motive fluid acting on the rear end of

the stem 3 will move the piston forwardly and to return the piston I herein provide suitable conduits 10 which communicate at one end with the forward portion of the bore receiving the head of the piston and at the other end with the bore receiving the stem 3. In the submitted embodiment of my invention four such conduits are shown, the same being arranged in pairs, the forward and rearward ends respectively of each pair communicating with arcuate grooves 11 formed in the large bore of the cylinder and arcual grooves 12 formed in the small bore. When the piston moves forwardly the rear end of the stem 3 uncovers the grooves 12 and thereby transfers motive fluid from the expansible chamber 4 to the expansible chamber 6 and as the effective cross-sectional area of the forward portion of the head is greater than that of the rearward end of the stem 3, the piston returns by differential action of the motive fluid.

For augmenting the supply to the conduits 10 I herein have provided a motive fluid supply passage or conduit 14 which in the submitted embodiment of my invention communicates with the live air conduit 7 and with the expansible chamber 4 at such a point that when the grooves 12 for the conduits 10 are open, the conduit 14 is permitted to supply motive fluid to the expansible chamber 4 whence it passes into the expansible chamber 6. With the conduits arranged as described, wire drawing of the fluid passing into the expansible chamber 4 is prevented when the conduits 10 are open, it being noted that the passage 14 provides a much shorter path for the motive fluid than that entering the chamber through the passages 9.

Preferably although not necessarily I admit motive fluid to the expansible chamber 5 when the piston is in its rearward position to increase the force of the blow imparted to the drill steel. For this purpose I have shown the forward portion of the stem 3 of reduced diameter as is indicated at 13. As may be determined from Fig. 1 when the piston is in its rearward position, communication is established between the groove 8 and the expansible chamber 5 which aids the motive fluid acting on the rearward stem 3 of the piston to force the piston forwardly.

For exhausting motive fluid from the chambers 5 and 6 I herein provide an ex-

haust port 15 which in the present embodiment of my invention is so located as to be overrun by the piston.

In the submitted embodiment of my invention, at the rear of the cylinder section receiving the large head of the piston is a cylinder section 17 which is exteriorly reduced to form a rearwardly extending sleeve 16 and in which is formed a bore receiving 10 and serving as a cylinder for the rearwardly extending stem 3. As shown the forward end of the cylinder section 17 is provided with a cylindrical part 17^a which enters the bore of the adjacent cylinder section, while 15 the portion of the cylinder section 17 between the part 17^a and the reduced portion 16 forms a flange abutting the end of the adjacent cylinder section. For closing the rearward end of the cylinder I herein provide a rear cylinder head 18 which herein fits over the end of the sleeve 16 and is mounted in spaced relation with the body portion of the cylinder section 17 by means 20 of the motor casing 19. For supporting the machine I may provide a handle 20 herein carried by the rear head 18. For supporting the drill steel I provide a chuck 21, which in the present embodiment of my invention I 25 rotate by means of a rotary type motor mounted in the casing 19.

In the submitted embodiment of my invention the rotary type motor above referred to comprises a central gear member 22 having the large gear teeth 22^a and smaller gear 30 teeth 22^b, and meshing therewith gear members 23 located at the side thereof. The central gear member 22 I have shown as rotatably mounted on the exterior of the sleeve 16, and as shown the motor is of a known 35 type in which the large gear teeth 22^a of the central gear fit the inner annular wall of the motor casing 19 and serve as pistons for converting the energy of the pressure fluid 40 into work, the gear members 23 serving as rotary abutments for the air acting on the pistons and having recesses 23^a permitting the pistons to pass by them. This motor as 45 shown is provided with inlets 24 which communicate with passages 25 having ports 26 50 communicating with the rearward end of the expandable chamber 4. The motor is further shown as provided with outlet ports 27 which communicate with passages 28 discharging to the atmosphere through ports 29. It will be noted from the above 55 construction that so long as motive fluid of sufficient pressure is admitted to the rearward end of the expandable chamber 4 the rotary motor for rotating the chuck will operate, 60 the air acting on the pistons 22^a causing the central gear or rotary piston member 22 to rotate and the latter imparting its rotation to the side gears or abutments 23. It will 65 also be observed that the stem 3 of the piston on its rearward stroke raises the pressure of

the air in the expandable chamber 4 and consequently increases the mean pressure of the motive fluid supplied the rotary motor.

I have found that it is of considerable advantage to supply the chuck rotating motor 70 with motive fluid from a point between the motive fluid supply connection and the conduit means effective to conduct the motive fluid compressed by the rearward stem of the piston to the motive fluid supply connection. Herein the passages 9 which connect the rearward end of the small bore of the cylinder to the motive fluid supply connection are preferably made as large as practical without unduly weakening the parts or 75 increasing the size of the machine, but no matter how large they are made they do not appear to prevent a material compression of the motive fluid in the small bore of the cylinder when the piston makes its return stroke. This I believe is due to the high speed of the piston. Therefore this portion 80 of the cylinder is substantially in restricted communication with the source of motive fluid supply solely by way of the passages 9 when the piston makes the final part of its 85 rearward stroke.

Surrounding the chuck I have shown a chuck casing 30 which herein provides a forward exterior bearing 31 for the chuck. At 90 the rearward end of the chuck I have herein provided a reduced portion 32 having an exterior bearing 33 at the end of the cylinder. For operatively connecting the motor and the chuck, I have shown shafts 34 which herein are driven by the gear members 23 secured thereto by keys 35. Preferably I provide a reduction gearing for operatively connecting the shafts and the chuck. For this purpose herein I form on the exterior 95 rearward portion of the chuck 21 gear teeth 36 adapted to mesh with gear teeth 37 formed on the yoke member 38 which surrounds the chuck. For operating the yoke member I have shown eccentric members 39 100 driven by the shafts 34, these eccentric members cooperating with the strap portions 40 of the yoke to gyrate the latter and thereby roll its toothed portion about the toothed portion of the chuck. By this means a powerful reduction gearing is provided. 105

Suitable bearings for the shafts may be provided. In the submitted embodiment four such bearings are provided for each shaft, namely those provided by the sleeve bearing 41 and the anti-friction bearing 42 respectively carried by the cylinder section 17 and the main portion of the cylinder and the end bearings 43 and 44 respectively carried by the rear head 18 and the chuck casing 30. 110

As will be readily understood by those skilled in this art, sludge, water and other foreign material may find its way into the chamber 45 of the chuck. For draining off 115

such material I may provide a suitable drainage passage which in the present embodiment of my invention is illustrated by the passage 46 leading to the atmosphere. 5 As will be obvious, the passage 46 will also serve as breather passage for the chamber 45 and thereby prevent, when the passage is connected to the atmosphere, a substantial increase or diminution of pressure in the 10 chamber 45 above or below the atmospheric pressure.

In the submitted embodiment of my invention, the exhaust port 15 communicates with the passage 46 by which the exhaust fluid is led to the atmosphere. 15 As will be readily noted, the exhaust fluid admitted from the port 15 into the passage 46 tends to force any material that may collect in the passage to the atmosphere.

20 As is usual with the type of machine herein submitted as illustrating my invention, I may conduct cleansing fluid to the work to cleanse the same. For this purpose, I herein provide the drill steel with the bore 47 which extends from the chamber 45 of the chuck to the cutting end of the steel. For conducting cleansing fluid to the bore of the steel, I provide a suitable tube 48 which in the present embodiment of my invention is 25 mounted in the rear cylinder head 18 and extends axially through the machine to the bore of the steel. As will be appreciated, if the air pressure in the chamber 45 is caused to build up air will be discharged 30 from said chamber into the bore 47 and hence to the work. This may be done for example either by admitting live air to the chamber 45 or by restricting the discharge end of the passage 46. Preferably but not 35 necessarily I employ mechanism which secures both of these results, which mechanism 40 will now be described.

45 For controlling the supply of motive fluid to the motors, the supply to the work and the exhaust and breather passages, I may use valvular mechanism which in the present embodiment of my invention takes the form of a valve 49 so constructed as to 50 coordinately control the conduits just indicated. This valve I have shown mounted in a casing carried by the cylinder section 55 17. As illustrated, the valve employed for this purpose is a conical turning plug having an interior chamber 50 supplied with live fluid by means of the connection 51. The plug is further provided with a side 60 passage 52. In the casing for the valve are formed three ports 53, 54 and 55, respectively connecting with the intake passage 7 leading to the percussive motor, the 65 combined exhaust and breather passage 46 and the atmosphere. Leading from the interior chamber 50 of the valve to its exterior surface is a port 56.

65 In the position of the valve shown by

Fig. 2, motive fluid is supplied to the passage 7 leading to the percussive motor and hence to the chuck rotating motor, while the ports 54 and 55 are connected by means of the side cavity 52 of the valve to the atmosphere. This is the normal running position of the valve. In this position if it is desired to blow the hole, the operator may suitably restrict the passage 55 as for example, by placing his hand over it or the valve may be turned in a counter-clockwise direction as viewed in Fig. 2 so that the passage 54 will be somewhat restricted, this restriction of course causing the exhaust pressure to build up in the chamber 45 and pass to the drill 70 steel. The port 56 is of such width that when this takes place, air will continue to be supplied to the passage 7 leading to the percussive motor. The restriction of the passage 55 thus described, besides blowing the hole, of course, to some extent slows up the percussive motor and decreases the blow on the steel.

Under some conditions, it is desirable to conduct live air at high pressure to the work. For this purpose, I may turn the valve as viewed in Fig. 2, in a counter-clockwise direction so as to interrupt the communication between the passage 46 and the atmosphere and to connect said passage with the port 56 so that live air may be supplied thereto. As will be obvious, under these conditions, the percussive motor will not operate. In order that under these conditions the drill steel may be rotated, I may so form the port 56 of the valve that when it supplies fluid to the passage 46 as just described, it will also supply fluid to the passage 53 whence it may pass to the chuck rotating motor through the conduit 7 and 105 the passages 9 and 25.

For suitably holding the parts of the machine in assembled relation, I may provide bolts 57, four of which are shown in the submitted embodiment of my invention. 110 These bolts extend from the chuck casing to the rear head 18.

In respect to the means for rotating the chuck the rock drill disclosed herein constitutes an improvement over the inventions 115 disclosed in my copending applications Serial No. 350,577, filed January 10, 1920, Serial No. 354,536, filed January 28, 1920, and Serial No. 355,494, filed January 31, 1920.

120 Although I have disclosed a specific embodiment of my invention for purposes of illustration it is to be understood that my invention is not limited to said embodiment and that wide deviations may be made 125 therefrom without departing from the spirit of my invention.

Claims.

1. In a drilling machine, a cylinder, a piston having a head and a rearwardly extend-

- ing portion, a chuck, a chuck rotating motor, said motor surrounding said portion, and means operatively connecting said motor and chuck. 65
5. 2. In a drilling machine, a cylinder, a piston having a head and a plurality of extending portions, a chuck, a chuck rotating motor, gearing means operatively connecting said motor and chuck, said motor surrounding one of said portions and said gearing surrounding another of said portions. 70
10. 3. In a drilling machine, a cylinder, a piston having a head and a rearwardly extending portion, a chuck, a chuck rotating motor of the rotary type, said motor surrounding said portion, and means operatively connecting said motor and chuck. 75
15. 4. In a drilling machine, a cylinder, a piston having a head and a plurality of extending portions, a chuck, a chuck rotating motor of the rotary type, gearing means operatively connecting said motor and chuck, said motor surrounding one of said portions, and said gearing surrounding another of 80
20. 5. In a drilling machine, a cylinder, a piston having a head and a rearwardly extending portion, a chuck, a chuck rotating motor comprising a rotary member for converting the energy of pressure fluid into work, said rotary member surrounding said portion, and means operatively connecting said motor and chuck. 85
25. 6. In a drilling machine, a cylinder, a piston having a head and a plurality of extending portions, a chuck, a chuck rotating motor comprising a rotary member for converting the energy of pressure fluid into work, said rotary member surrounding said portion, and means operatively connecting said motor and chuck. 90
30. 7. In a drilling machine, a cylinder, a piston having a head and an extending portion, a chuck, a chuck rotating motor, said motor surrounding said portion, means operatively connecting said motor and chuck, said portion providing a pressure surface, and means for admitting motive fluid to said cylinder to exert a pressure on said surface. 95
35. 8. In a drilling machine, a cylinder, a piston having a head and an extending portion, a chuck, a chuck rotating motor, said motor surrounding said portion, means operatively connecting said motor and chuck, conduit means for admitting motive fluid to said cylinder, conduit means for exhausting such motive fluid, and one of said conduit means being controlled by said portion. 100
40. 9. In a drilling machine, a cylinder, a piston having a head and an extending portion, a chuck, a chuck rotating motor of the rotary type, said motor surrounding said portion, and said gearing surrounding another of said portions. 105
45. 10. In a drilling machine, a cylinder, a piston having a head and an extending portion, a chuck, a chuck rotating motor comprising a rotary member for converting the energy of pressure fluid into work, said rotary member surrounding said portion, means operatively connecting said motor and chuck, conduit means for admitting motive fluid to a portion of the cylinder for operating said piston, conduit means for exhausting such motive fluid, and one of said conduit means being controlled by said portion. 110
50. 11. In a drilling machine, a cylinder, a piston having a head and an extending portion, a chuck, a chuck rotating motor of the rotary type, said motor surrounding said portion, means operatively connecting said motor and chuck, conduit means for admitting motive fluid to a portion of the cylinder for operating said piston, conduit means for exhausting such motive fluid, and one of said conduit means being controlled by said portion. 115
55. 12. In a drilling machine, a cylinder, a piston having a head and an extending portion, a chuck, a chuck rotating motor comprising a rotary member for converting the energy of pressure fluid into work, said rotary member surrounding said portion, means operatively connecting said motor and chuck, conduit means for admitting motive fluid to a portion of the cylinder for operating said piston, conduit means for exhausting such motive fluid, and one of said conduit means being controlled by said portion. 120
60. 13. In a drilling machine, a cylinder, a piston having oppositely extending portions, a chuck, a chuck rotating motor, gearing operatively connecting said motor and chuck, said motor surrounding one of said portions, and said gearing surrounding the other portion and said chuck. 125
65. 14. In a drilling machine, a cylinder, a piston having a portion of reduced diameter, a chuck, a chuck rotating motor, means operatively connecting said motor and chuck, said motor surrounding said portion of reduced diameter, and means controlled by said portion for admitting motive fluid to a portion of said cylinder for operating the piston in one direction. 130
70. 15. In a drilling machine, a cylinder, a piston having a head and oppositely extending portions, a chuck, a chuck rotating motor surrounding one of said portions, a gearing surrounding the other of said portions, and a shaft operatively connecting said motor and gearing. 135
75. 16. In a drilling machine, a cylinder, a

piston having a head and oppositely extending portions, a chuck, a chuck rotating motor of the rotary type and adapted to surround one of said portions, a gearing adapted to surround the other of said portions, and a shaft operatively connecting said motor and gearing.

17. In a drilling machine, a cylinder, a piston having a head and oppositely extending portions, a chuck, a chuck rotating motor comprising a rotary member for converting the energy of pressure fluid into work, said rotary member surrounding one of said portions, a gearing surrounding the other of said portions, and a shaft operatively connecting said motor and gearing.

18. In a drilling machine, a cylinder, a piston having a head and oppositely extending portions, a chuck, a chuck rotating motor comprising a rotary member for converting the energy of pressure fluid into work surrounding one of said portions, a member transversely disposed with relation to said rotary member and operatively connected therewith, a gearing surrounding the other of said portions and a shaft operatively connecting said member and gearing.

19. In a drilling machine, a cylinder, a piston having a head and oppositely extending portions, a chuck, a chuck rotating motor comprising a rotary member for converting the energy of pressure fluid into work surrounding one of said portions, a gear operatively connected with said rotary member, a gearing surrounding the other of said portions, and a shaft operatively connecting said gear and gearing.

40 20. In a drilling machine, a cylinder, a piston having a head and oppositely extending portions, a chuck, a chuck rotating motor comprising a rotary member surrounding one of said portions, a plurality of rotary members forming with the first mentioned rotary member a plurality of expandable chambers, a gear connection between said first mentioned rotary member and each of said plurality of rotary members, reduction gearing surrounding the other of said portions, and shafts connecting each of said plurality of rotary members to said gearing.

21. In a drilling machine, a piston having a rearward extension, a drill steel for operation by said piston, a motor for rotating said steel having a rotary member for converting the energy of pressure fluid into work surrounding said extension, and means operatively connecting said rotor and steel.

60 22. In a drilling machine, a piston having a head and a rearward extension, a drill steel for operation by said piston, a rotary motor for rotating said steel, said motor being located rearwardly of said head and having a rotary part in substantially axial

alignment therewith, and means including a forwardly extending shaft at the side of said head operatively connected to said motor and a gyratory yoke in substantially axial alignment with said steel driven by said shaft for operatively connecting said motor and steel. 65 70

23. In a drilling machine, a piston having a head and a rearward extension, a drill steel for operation by said piston, a motor for rotating said steel located rearwardly of said head and comprising means including a pair of rotary members forming an expansible chamber one of which members is in substantially axial alignment with said head, and means including a forwardly extending shaft at the side of said head and a gyratory yoke in substantially axial alignment with said steel driven by said shaft for operatively connecting the other of said rotary members and steel. 75 80 85

24. In a drilling machine, a piston having a head and a rearward extension, a drill steel for operation by said piston, a motor for rotating said steel and located rearwardly of said head in axial alignment with said steel, and means including a forwardly extending shaft at the side of said head operatively connected to said motor and a gyroscopic yoke in substantially axial alignment with said steel driven by said shaft for operatively connecting said motor and steel. 90 95

25. In a drilling machine, a piston having a head and a rearward extension, a drill steel for operation by said piston, a motor for rotating said steel and located rearwardly of said head, said motor having means including a pair of gears forming an expansible chamber one of which gears is located in substantially axial alignment with said steel, a forwardly directed shaft for rotating said steel directly driven by the other of said gears, an eccentric driven by said shaft, and a gyratory yoke in substantially axial alignment with said steel driven by said eccentric. 100 105

26. In a drilling machine, a cylinder 110 having a piston provided with an extension 3, a drill steel, and a motor for rotating said steel comprising the annular fluid pressure actuated member 22 formed to permit said extension to pass through it. 115

27. In a drilling machine, a piston having a rearward extension, a cylinder, a motor having a rotary member for converting the energy of pressure fluid into work surrounding said extension, a shaft extending through said cylinder and operatively connected to said rotary member, a drill steel, and gearing driven by said shaft for rotating said steel. 120

28. In a drilling machine, a piston having 125 the extension 3, a motor having the gears 22 and 23, one of said gears being formed to permit said extension to pass through it, a

shaft 34 driven by one of said gears, a chuck, and gearing comprising the toothed member 38 for driving said chuck.

29. In a rock drill, a cylinder, a piston in said cylinder, said piston having a head and forward and rearward extensions, a chuck having an opening for receiving said forward extension of said piston, external gear teeth on said chuck, an internally toothed 5 yoke surrounding said chuck and meshing with said external gear teeth, and a motor for operating said yoke and surrounding said rearward extension of said piston.

30. In a rock drill, a cylinder, a piston in said cylinder, said piston having a head and forward and rearward extensions, a chuck having an opening for receiving said forward extension of said piston, external gear teeth on said chuck, an internally toothed 10 yoke surrounding said chuck and meshing with said external gear teeth, eccentrics for operating said yoke, a motor for actuating said eccentrics, and said motor surrounding said rearward extension of said piston.

25 31. In a rock drill, a cylinder, a piston in said cylinder, said piston having a rearward extension, a motor surrounding said extension, a chuck, a gyratory member for driving said chuck, and means for causing said motor to actuate said gyratory member.

32. In a rock drill, a cylinder, a piston in said cylinder, said piston having a rearward extension, a motor surrounding said extension, a chuck, a gyratory member for driving said chuck, an eccentric member for actuating said gyratory member, and means for transmitting the power of said motor to said eccentric member.

40 33. In a rock drill, a cylinder, a piston in said cylinder, said piston having a rearward extension, a motor surrounding said extension, a chuck, oppositely disposed eccentrics driven by said motor, a yoke mounted on said eccentrics, and said yoke carrying gear 45 teeth meshing with gear teeth carried by said chuck.

34. A rock drill of the hammer type having a reciprocating piston, a chuck and a motor delivering unidirectional motion for 50 rotating said chuck, said piston having a head and a rearward extension, a cylinder for said piston, said cylinder being exteriorly reduced adjacent said rearward extension of said piston, a rearward facing 55 shoulder on said cylinder at the forward end of the reduced portion of said cylinder, a back head for said cylinder having a portion extending radially beyond the reduced portion of said cylinder, and said motor being located between said extending portion 60 of said back head and said rearwardly facing shoulder.

35. A rock drill of the hammer type having a reciprocating piston, a chuck and 65 a motor delivering unidirectional motion for

rotating said chuck, said piston having a head and a rearward extension, said cylinder having a section for said head and a section for said extension, the section for said extension having a flange and a reduced diameter portion, a casing for said motor abutting said flange, and a common back head for said cylinder and said casing.

36. A rock drill of the hammer type having a reciprocating piston, a chuck and a motor delivering unidirectional motion for 70 rotating said chuck, said piston having a head and a rearward extension, a cylinder having a cylinder section provided with a bore for said head, said cylinder having a separate cylinder section provided with a bore for said rearward extension, said separate cylinder section being of smaller cross-section than said first mentioned cylinder section, and having formed thereon a rearwardly facing shoulder, said motor for rotating said chuck being located behind said shoulder exteriorly of said separate cylinder section and having a casing carried by said separate cylinder section, and means for 80 holding said cylinder sections in assembled relation.

37. A rock drill having a chuck, a hammer piston and motor for driving said chuck, said hammer piston having a head and a 85 rearward extension, said cylinder having bores receiving said head and rearward extension of said piston, said cylinder being of reduced cross-section exteriorly of said extension and having a rearwardly facing 90 shoulder at the forward end of the portion of reduced cross-section, said motor for rotating said chuck being located at the portion of reduced cross section behind said shoulder, and a gyratory member geared to 95 said chuck and driven by said motor.

38. In a motor, a cylinder having a small bore and a larger bore, a piston having portions fitting said bores, conduit means for admitting fluid to one of said bores, conduit means controlled by said piston for transferring such fluid to the other of said bores, and other conduit means for admitting fluid to the same bore as the first conduit means when the second conduit means 110 is operating.

39. In a motor, a cylinder having a small bore and a larger bore, a piston having portions fitting said bores, conduit means for supplying fluid to said small bore, a conduit 115 connecting said small bore to said larger bore and controlled by said piston, and other conduit means controlled by said piston for supplying fluid to said small bore when said passage is opened.

40. In a motor, a cylinder having a small bore and a larger bore, a piston having portions fitting said bores, conduit means for constantly supplying fluid to said small bore, a conduit connecting said small bore 120

- to said larger bore and controlled by said piston, and other conduit means controlled by said piston for supplying fluid to said small bore when said passage is opened.
41. In a motor having a cylinder and a piston providing portions of small and larger effective cross-sectional area, conduit means for admitting fluid to one of said portions, conduit means for transferring such fluid to the other of said portions, and other conduit means for admitting fluid to the same portion as the first conduit means when the second conduit means is operating.
42. In a motor having a cylinder and a piston providing portions of small and larger effective cross-sectional area, conduit means for supplying fluid to the portion of small area, a conduit connecting the last named portion to the other portion and controlled by the piston, and other conduit means adapted to be controlled by said piston for supplying fluid to said small portion when said passage is opened.
43. In a motor having a cylinder and a piston providing portions of small and larger effective cross-sectional area, conduit means for constantly supplying fluid to the portion of small area, a conduit connecting the last named portion to the other portion and controlled by the piston, and other conduit means controlled by said piston for supplying fluid to said small portion when said passage is opened.
44. In a percussive motor for drill steels, a piston having a head and an extension, a cylinder for said piston, a source of motive fluid supply, and a pair of spaced ports connecting said source to the cylinder portion for said extension and controlled by said extension to admit fluid from one port to one side of said head and from the other port to the opposite side of said head.
45. In a percussive motor for drill steels, a piston having a head and an extension, a cylinder for said piston, a source of motive fluid supply, a pair of spaced ports connecting said source to the cylinder portion for said extension and controlled by said extension to admit fluid from one port to one side of said head and from the other port to the opposite side of said head, and means for admitting fluid and causing it to act constantly on the end of said extension.
46. In a motor, a cylinder, a piston in said cylinder, said piston having portions of small and larger effective cross-sectional area, conduit means for supplying fluid to act continuously on the portion of small area, a conduit connecting the last named portion to the other portion and adapted to be controlled by the piston, and other conduit means adapted to be controlled by said piston for supplying fluid to said small portion when said passage is opened.
47. In a percussive motor for drill steels,
- a piston having the portions 1 and 3, a cylinder for said portions, passages 7 and 14 opening into the bore of the cylinder for the portion 3, the passages 10 leading to the end of the cylinder bore for the portion 1, and said portion 3 placing said passages into communication when the piston is at one end of its stroke.
48. In a drilling machine, a cylinder, a piston therein, said cylinder and piston forming a chamber, a source of motive fluid, conduit means for constantly supplying said chamber with motive fluid from said source, a chuck, a chuck rotating motor having an intake, and conduit means for uninterruptedly supplying motive fluid from said chamber to said intake.
49. In a drilling machine, a cylinder, a piston therein, said cylinder and piston forming a differential piston chamber, a source of motive fluid, conduit means for constantly supplying said chamber with motive fluid from said source, a chuck, a chuck rotating motor having an intake, and conduit means for uninterruptedly supplying motive fluid from said chamber to said intake.
50. In a drilling machine, a cylinder, a piston therein, said cylinder and piston forming a chamber, means for constantly supplying said chamber with motive fluid, a chuck, a chuck rotating motor having an intake and surrounding said chamber, and conduit means connecting said chamber and intake.
51. In a drilling machine, a cylinder, a piston therein, said cylinder and piston forming a chamber, a source of motive fluid, conduit means for constantly supplying said chamber with motive fluid from said source, a chuck, a chuck rotating motor having an intake and located adjacent said chamber, and conduit means for uninterruptedly supplying motive fluid from said chamber to said intake.
52. In a drilling machine, a cylinder, a piston therein, said cylinder and piston forming a chamber, a drill steel, a motor for rotating said steel and having an intake, means for admitting fluid to said chamber to act continuously on the same pressure area of said piston, and means for uninterruptedly conducting motive fluid from said chamber to said intake.
53. In a drilling machine, a cylinder, a piston therein, said cylinder and piston forming an expansible chamber, a drill steel, a rotary engine for rotating said steel and having an intake, a source of motive fluid, conduit means providing constant communication between said source and said intake, and said conduit means including said expansible chamber.
54. In a drilling machine, a cylinder, a piston therein, said cylinder and piston

forming a differential piston chamber, means for supplying said chamber with pressure fluid and causing it to act continuously on said piston, a chuck rotating motor having an intake, and conduit means for uninterruptedly supplying motive fluid from said chamber to said intake.

55. In a drilling machine, a piston having a head and an extension, a cylinder having bores for said head and extension, a drill steel, a motor for rotating said steel and having an intake, a source of motive fluid, conduit means connecting said source with the bore for said extension, and conduit means for uninterruptedly supplying said intake with motive fluid from said last named bore.

56. In a drilling machine, a piston having a head and an extension, a cylinder having bores for said head and extension, a drill steel, a motor for rotating said steel and having an intake, means for admitting motive fluid from a source of supply to the bore for said extension for acting continuously on the rearward end of said extension, means for admitting said motive fluid from said bore for said extension to the bore for said head, and means for supplying motive fluid uninterruptedly from the rearward end of said bore for said extension to said intake.

57. In a drilling machine, a piston having the portion 3, a cylinder forming with said portion the expansible chamber 4, a drill steel, a motor for rotating said steel and having an intake, the passage 25 uninterruptedly connecting said chamber to said intake, and conduit means independent of said passage 25 for constantly supplying said chamber 4 with motive fluid.

58. In a drilling machine, a percussive motor having a cylinder and piston, said cylinder and piston forming a chamber, means for constantly admitting fluid to said chamber, a chuck rotating motor having an intake, conduit means connecting said chamber and intake, an exhaust discharge conduit for said percussive motor, and means for rendering said exhaust discharge conduit inoperative while permitting an admission of fluid to said chamber.

59. In a drilling machine, a percussive motor having a cylinder and piston, said cylinder and piston forming a chamber, means for constantly admitting fluid to said chamber, a chuck rotating motor having an intake, conduit means connecting said chamber and intake, an exhaust discharge conduit for said percussive motor, conduit means leading to the work and connecting with said exhaust discharge conduit, and means for rendering said exhaust discharge conduit inoperative to discharge exhaust and simultaneously to supply fluid thereto

while permitting an admission of fluid to 65 said chamber.

60. In a drilling machine, a cylinder, a piston therein, said cylinder and piston forming a chamber, means for constantly supplying said chamber with motive fluid, a chuck, a chuck rotating motor having an intake, conduit means connecting said chamber and intake, and means for rendering said piston inoperative while permitting a supply to said chamber.

61. In a drilling machine, a cylinder, a piston therein, said cylinder and piston forming a differential piston chamber, means for constantly supplying said chamber with motive fluid, a chuck, a chuck rotating motor having an intake, conduit means connecting said chamber and intake, and means for rendering said piston inoperative while permitting a supply to said chamber.

62. In a drilling machine, a percussive motor having a piston and cylinder and an exhaust discharge, said piston and cylinder forming a chamber, a chuck rotating motor having an intake, a conduit connecting said intake and chamber, and coordinated controlling means providing in one position thereof a supply of motive fluid to said chamber and permitting the operation of said exhaust discharge and in another position thereof to provide a supply of motive fluid to said chamber and while rendering said exhaust discharge inoperative.

63. In a drilling machine, a percussive motor having a piston and cylinder and an exhaust discharge, said piston and cylinder forming a chamber, a chuck rotating motor having an intake, a conduit connecting said intake and chamber, coordinated controlling means permitting in one position thereof the operation of said exhaust discharge and in another position rendering said exhaust discharge inoperative while supplying motive fluid to said chamber in both positions and to the exhaust discharge in the second position, and conduit means connecting said exhaust discharge to the work.

64. In a drilling machine, a drill steel rotating motor having an intake, a hammer motor having an intake and an exhaust, means providing for the simultaneous connection of the intakes of both motors to a source of motive fluid supply, and means for connecting the exhaust of said hammer motor to said source without interrupting the supply to said intakes.

65. In a drilling machine, a drill steel rotating motor, a hammer motor, means for supplying pressure fluid from a source of pressure fluid to said hammer motor and hence to said drill steel rotating motor, and means for connecting the exhaust discharge conduit of said hammer motor to said source

- without interrupting the supply to said hammer motor.
66. In a drilling machine, a drill steel rotating motor, a hammer motor, means for supplying pressure fluid from a source of motive fluid to said hammer motor and hence to said drill steel rotating motor, an exhaust discharge conduit means leading to the atmosphere for discharging the exhaust of said hammer motor, means connecting said conduit means to the work, and means for connecting said exhaust discharge conduit means to said source of pressure fluid without interrupting the supply to said hammer motor.
67. In a percussive motor for drill steels, a source of pressure fluid supply, an intake and an exhaust for said motor, an independent motor for rotating the drill steel, means for supplying said independent motor with motive fluid conducted through said intake, and means for at will optionally connecting to said source either said intake alone or both said intake and exhaust.
68. In a percussive motor for drill steels, a source of pressure fluid supply, an intake and an exhaust for said motor, an independent motor for rotating said drill steel, said independent motor being supplied with pressure fluid passing through said intake, a connection between said percussive motor and the work, and means for at will optionally connecting to said source either said intake alone or both said intake and exhaust.
69. In a percussive motor for drill steels, a source of pressure fluid supply, an intake and an exhaust for said motor, conduit means for conducting pressure fluid from said motor to the drill hole, an auxiliary motor for rotating said drill steel operated by pressure fluid passing through said intake, and means for at will optionally connecting to said source either said intake alone or both said intake and exhaust and in both instances without interrupting the exhaust of said auxiliary motor.
70. In a percussive motor for drill steels, a source of pressure fluid supply, an intake for said motor, a chuck having a chamber, a conduit connecting said chamber to the atmosphere, a drill steel having a bore in communication with said chamber, and means for at will optionally connecting to said source either said intake or both said intake and conduit.
71. In a percussive motor for drill steels, a source of pressure fluid supply, an intake and an exhaust for said motor, a chuck having a chamber, a conduit connecting said chamber to said exhaust, a drill steel having a bore in communication with said chamber, and means for at will optionally connecting to said source either said intake or both said intake and exhaust.
72. In a percussive motor for drill steels, a source of pressure fluid supply, an intake for said motor, an auxiliary motor having an intake and exhaust, the intake of said auxiliary motor being supplied from the intake of said percussive motor, a chuck having a chamber, a conduit connecting said chamber to the atmosphere, and means for at will optionally connecting to said source either said intake or both said intake and exhaust.
73. In a percussive motor for drill steels, a source of pressure fluid supply, an intake and an exhaust for said motor, an auxiliary motor having an intake and exhaust, said intake of said auxiliary motor being supplied with pressure fluid from the intake of said percussive motor, a chuck having a chamber, a conduit connecting said chamber to said exhaust of said percussive motor, and means for at will optionally connecting to said source either said intake of said percussive motor alone or both said intake and exhaust of said percussive motor and in both instances without interrupting the exhaust of said auxiliary motor.
74. In a percussive motor for drill steels, a source of pressure fluid supply, intake and exhaust conduits for said motor, a hollow drill steel having its bore in permanent communication with the exhaust conduits, and coordinated valvular means for at will optionally connecting to said source either said intake conduit alone or both said intake and exhaust conduits.
75. In a percussive motor for drill steels, a source of pressure fluid supply, intake and exhaust conduits for said motor, conduit means for permanently connecting the exhaust conduit to the drill hole, and coordinated valvular means for at will optionally connecting to said source either said intake alone or both said intake and exhaust.
76. In a percussive motor for drill steels, a source of pressure fluid supply, an intake and an exhaust for said motor, conduit means for permanently connecting the exhaust conduit to the drill hole, an auxiliary motor having its intake supplied with pressure fluid from the intake of said percussive motor, and coordinated valvular means for at will optionally connecting to said source either said intake of said percussive motor or both said intake and exhaust of said percussive motor and in each instance without interrupting the exhaust of said auxiliary motor.
77. In a percussive motor for drill steels, a source of pressure fluid supply, an intake for said motor, a chuck having a chamber, a drill steel having a bore in communication with said chamber, a conduit connecting said chamber to the atmosphere, and coordinated valvular means for at will optionally con-

neeting to said source either said intake alone or both said intake and conduit.

78. In a percussive motor for drill steels, a source of pressure fluid supply, an intake and an exhaust for said motor, a chuck having a chamber, a conduit permanently connecting said chamber to said exhaust, and coordinated valvular means for at will optionally connecting to said source either said intake or both said intake and exhaust.

79. In a percussive motor for drill steels, a source of pressure fluid supply, an intake for said motor, an auxiliary motor supplied with pressure fluid from said intake, a chuck having a chamber, a conduit connecting said chamber to the atmosphere, and coordinated valvular means for at will optionally connecting to said source either said intake or both said intake and conduit and in both instances without interrupting the exhaust of said auxiliary motor.

80. In a percussive motor for drill steels, a source of pressure fluid supply, an intake and an exhaust for said motor, an auxiliary motor supplied with pressure fluid from said intake, a chuck having a chamber, a conduit connecting said chamber to said exhaust, and coordinated valvular means for at will optionally connecting to said source either said intake or both said intake and exhaust and in both instances without interrupting the exhaust of said auxiliary motor.

81. In a percussive motor for drill steels, a source of pressure fluid supply, an intake and an exhaust for said motor, and a single valve for at will optionally connecting to said source either said intake for causing said motor to operate or both said intake and exhaust for causing said motor to cease operation.

82. In a percussive motor for drill steels, a source of pressure fluid supply, an intake and an exhaust for said motor, means for conducting exhaust pressure fluid from said motor to the drill hole, and a single valve for at will optionally connecting to said source either said intake for causing said motor to operate and the drill hole to be supplied or both said intake and exhaust for causing said motor to cease operating and the drill hole to be supplied.

83. In a percussive motor for drill steels, a source of pressure fluid supply, an intake and an exhaust for said motor, conduit means supplying pressure fluid from said motor to the drill hole, an auxiliary motor supplied with pressure fluid from said intake, and a single valve for at will optionally connecting to said source either said intake or both said intake and exhaust and in both instances without interrupting the exhaust of said auxiliary motor.

84. In a percussive motor for drill steels, a source of pressure fluid supply, an intake for said motor, a chuck having a chamber, a

conduit connecting said chamber to the atmosphere independently of the drill hole, and a single valve for at will optionally connecting to said source either said intake or both said intake and conduit.

85. In a percussive motor for drill steels, a source of pressure fluid supply, an intake and an exhaust for said motor, a chuck having a chamber, a conduit connecting said chamber to said exhaust, and a single valve for at will optionally connecting to said source either said intake or both said intake and exhaust.

86. In a percussive motor for drill steels, a source of pressure fluid supply, an intake for said motor, an auxiliary motor supplied with pressure fluid from said intake, a chuck having a chamber, a conduit connecting said chamber to the atmosphere, and a single valve for at will optionally connecting to said source either said intake or both said intake and conduit and in both instances without interrupting the exhaust of said auxiliary motor.

87. In a percussive motor for drill steels, a source of pressure fluid supply, an intake and an exhaust for said motor, an auxiliary motor supplied with pressure fluid from said intake, a chuck having a chamber, a conduit connecting said chamber to said exhaust, and a single valve for at will optionally connecting to said source either said intake or both said intake and exhaust and in both instances without interrupting the exhaust of said auxiliary motor.

88. In a drilling machine, a percussive motor, a motive fluid supply connection, an intake for said percussive motor, a chuck carrying a hollow drill steel, the passage 46 in communication with the interior of said chuck, and the valve 49 for connecting the passage 46 either to the atmosphere or to said motive fluid supply connection.

89. In a drilling machine, a percussive motor, a motive fluid supply connection, an intake for said percussive motor, a chuck carrying a hollow drill steel, a motor for rotating said chuck and having the intake port 26, the passage 46 in communication with the interior of said chuck, and the valve 49 for connecting the passage 46 either to the atmosphere or to said motive fluid supply connection and in each case connecting the intake for said percussive motor to said motive fluid supply connection.

90. In a drilling machine, a cylinder, a piston therein, said piston having an extending portion, a chuck rotating motor comprising a rotary member for converting the energy of pressure fluid into work surrounding said portion, and means including a conduit surrounded by said rotary member for supplying motive fluid to operate said piston.

91. In a motor, a piston having a head and

an extending portion, a cylinder having a section providing a bore for said head portion, a closure for said bore comprising a cylinder section having a wall forming a bore for said portion, a chuck rotating motor comprising a rotary member for converting the energy of pressure fluid into work surrounding said wall, and means including a conduit formed in said wall for supplying motive fluid to operate said piston.

92. In a drilling machine, a cylinder, a piston in said cylinder, said piston having a head and a rearward extension of reduced diameter, a motor having an annular external gear surrounding said rearward extension, a gear at the side of said extension meshing with said annular gear, a chuck, and reduction gearing operatively connecting one of said gears to said chuck.

93. In a drilling machine, a cylinder, a piston in said cylinder, said piston having a head and a rearward extension of reduced diameter, a motor having an annular external gear surrounding said rearward extension, a gear at the side of said extension meshing with said annular gear, a shaft driven by said second gear, a chuck, and reduction gearing operatively connecting said shaft and chuck.

94. In a drilling machine, a cylinder, a piston in said cylinder, said piston having a head and a rearward extension of reduced diameter, a motor having an annular external gear surrounding said rearward extension, a pair of gears meshing with said annular gear, said pair of gears being disposed at opposite sides of said annular gear, a shaft driven by one of said pair of gears, a chuck, and reduction gearing operatively connecting said shaft and chuck.

95. In a drilling machine, a cylinder, a piston in said cylinder, said piston having a head and a rearward extension of reduced diameter, a motor having an annular external gear surrounding said rearward extension, a pair of gears meshing with said annular gear, said pair of gears being disposed at opposite sides of said annular gear, separate shafts driven by each of said pair of gears, a chuck, and reduction gearing operatively connecting said chuck and shafts.

96. In a rock drill, a drilling tool, a hammer and a motor for operating said tool, said motor having an intake and an exhaust and substantially continuously conducting motive fluid from said intake to said exhaust for operation of said motor, means for supplying motive fluid to said hammer and motor, and means for causing the hammer to impart energy to the motive fluid supplied the motor.

97. In a rock drill, a drilling tool, a hammer and a motor for operating said tool, said motor having an intake and an ex-

haust and substantially continuously conducting motive fluid from said intake to said exhaust for operation of said motor, means for supplying motive fluid for operating said hammer, means for cushioning said hammer by fluid pressure, and means for utilizing the energy of compression for operating said motor.

98. In a rock drill, a drilling tool, a hammer and a motor for operating said tool, said motor having an intake and an exhaust and substantially continuously conducting motive fluid from said intake to said exhaust for operation of said motor, means for supplying motive fluid for operating said hammer, and means for converting the kinetic energy of said hammer into fluid pressure energy for operating said motor.

99. In a rock drill, a drilling tool, a hammer and a motor for operating said tool, said motor having an intake and an exhaust and substantially continuously conducting motive fluid from said intake to said exhaust for operation of said motor, means for supplying motive fluid to said hammer and motor and means for causing the motive fluid supplied said hammer to augment the energy of the motive fluid supplied said motor.

100. In a rock drill, a drilling tool, a hammer and a motor for operating said tool, said motor having an intake and an exhaust and substantially continuously conducting motive fluid from said intake to said exhaust for operation of said motor, means providing a pressure area for said hammer and an opposed pressure area, means for admitting fluid to said areas and for causing that acting on one of said areas to move the hammer to compress the fluid behind to the other, and means for conducting such compressed fluid to said motor.

101. In a rock drill, a drilling tool, a hammer and a motor for operating said tool, means providing a pressure area and relatively larger opposed pressure area for said hammer, cylinder portions for said areas, a motive fluid supply, means for connecting the cylinder portion for said first named area to said supply and effective to restrict return flow, means for intermittently connecting the cylinder portion for said opposed area to said supply, and a normally permanently open connection from the cylinder portion for the first named area to said motor.

102. In a rock drill, a drilling tool, a hammer for operating said tool, said hammer having a smaller and a larger diameter portion, a cylinder for said hammer, a source of motive fluid supply, a connection between said source and the cylinder including passages controlled by said smaller diameter portion for admitting fluid to said cylinder to act on said larger diameter por-

tion, a connection controlled by said smaller diameter portion for compressing motive fluid, a motor for actuating said tool, and a normally permanently open connection for conducting such compressed fluid to said motor for operating it.

103. In a rock drill, a drilling tool, a motor for operating said tool, said motor having an intake and an exhaust and substantially continuously conducting motive fluid from said intake to said exhaust for operation of said motor, a hammer for operating said tool and having opposed surfaces, means for causing motive fluid to act on said surfaces for reciprocating said hammer, a plunger connected to reciprocate with said hammer, and means for causing said plunger to compress motive fluid for operating said motor.

20 104. In a rock drill, a drill steel, a hammer having an intermittent larger pressure

surface and an opposed pressure surface in constant and restricted communication with a source of motive fluid, a cylinder having a portion providing an abutment for said opposed surface, a rotary motor for rotating said steel, and a motor supply connection from said cylinder portion to said motor.

105. In a rock drill, a drill steel, a hammer having two opposed intermittent pressure surfaces and a forwardly acting pressure surface in constant and restricted communication with a source of motive fluid, a cylinder having a portion providing an abutment for said forwardly acting surface, a rotary motor for rotating said steel, and a motor supply connection from said cylinder portion to said motor.

In testimony whereof, I have signed my name to this specification.

GEORGE H. GILMAN.
